ACCESSORY DRIVE FOR FREE-PISTON UNITS

Ralph J. Hooker, Hamilton, Ohio, assignor to
 United Aircraft Corporation, East Hartford,
 Conn., a corporation of Delaware

Application March 12, 1948, Serial No. 14,468

9 Claims. (Cl. 123—46)

1

This invention relates to free-piston units and particularly to an arrangement for providing a rotating motion for driving accessories for the unit.

The usual free-piston unit has opposed reciprocating piston elements which are free to move within the engine-and-compressor cylinders and are caused to move synchronously by a linkage which interconnects the pistons and which has, in general, an interconnecting element having an oscillatory motion. This type of free-piston unit has no crankshaft, and, accordingly, no rotating part. It is advantageous to have a rotary drive which might be used, for example, for circulating cooling fluid through the engine piston or around the engine cylinders or for supplying lubricant or fuel to the unit. A feature of the invention is such a drive actuated by the unit and so arranged as to rotate continuously in one direction during operation of the unit.

In free-piston units operating at high capacity, the pistons have a high frequency of reciprocation and the interconnecting linkage has the same high frequency. It has been proposed to operate a hydraulic pump in response to the piston reciprocation to provide fluid under pressure, such as lubricant or fuel. At the high frequencies now obtainable in these units, the hydraulic pump becomes inoperative by reason of the inertia of the valve mechanism and of the liquid that is cyclically accelerated. To overcome this difficulty, a feature of the invention is an oscillating centrifugal pump which utilizes the inertia of the fluid and which is constructed to be actuated by the synchronizing linkage. Another feature is the use of a hydraulic motor adapted to be driven by the fluid under pressure provided by the centrifugal pump. One feature of the invention is an arrangement of the pump and motor is such a manner that the fluid used is circulated in a substantially annular path.

A feature of the invention is an oscillating vane type of pump cooperating with a vane type motor similar to a turbine runner and associated with stationary guide vanes which direct the fluid from the pump against the motor vanes.

Other objects and advantages will be apparent from the specification and claims, and from the accompanying drawing which illustrates an embodiment of the invention.

Fig. 1 is diagrammatic sectional view through the free-piston unit showing the rotary drive in elevation.

Fig. 2 is a sectional view through the hydraulic pump and motor of the rotary drive.

2

Fig. 3 is a sectional view substantially along the line 3—3 of Fig. 2.

Fig. 4 is a sectional view substantially along the line 4—4 of Fig. 2, showing the stator vanes and the vanes on the motor.

The free-piston unit combines an engine cylinder 2, having opposed reciprocating pistons 4 and 6 therein, to which compressor pistons 8 and 10 are integrally connected. The compressor pistons 8 and 10 reciprocate in compressor cylinders 12 and 14 which may form an integral part of the surrounding housing 16 for the unit. Sleeves 18 and 20, attached to the engine and compressor pistons, complete the reciprocating piston assemblies. The sleeves reciprocate over air spring pistons 22 and 24 and form, with said pistons, air springs which move the opposed piston assemblies toward each other on the compression stroke.

20 The piston assemblies are moved apart by the burning of fuel injected into the engine cylinder as by fuel nozzle 26. The assemblies are maintained at equal but varying distances from the center of the engine cylinder by a linkage which 25 includes projecting rods 28 and 30 extending from the compressor pistons 8 and 10 and meshing with a pinion 32. It will be apparent that the pinion 32 oscillates when the piston assemblies reciprocate within the respective cylinders.

30 An intake manifold 34 surrounds the unit, the outer housing 16 forming the outside wall of the manifold, and conducts air to inlet valves 36 in the outer ends of the compressor cylinders. The air compressed in the cylinders is discharged

35 through valves 38 into chambers 40 and 42 at opposite ends of the unit. These chambers are interconnected by a duct 44 which also communicates with a chamber 46 surrounding the engine cylinder. From the chamber 46 the air enters the engine cylinder through ports 48. Exhaust ports 50 permit the exhaust gas to escape from the engine cylinder into the exhaust pipe 52.

45 For the purpose of converting the reciprocating motion of the pistons or the oscillatory motion of the pinion 32 into a rotary motion for the purpose of driving accessories, the shaft 54 on which the pinion is mounted carries at its end a centrifugal pump in the form of an impeller

50 56 located within a housing 58. The impeller vanes 60 function, during the oscillation of the impeller, to force fluid outwardly against a cap 62, forming a part of the housing 58. The cap forms the outer part of an annular path 64 through which the fluid is circulated, the center

55 of which is defined by the housing 58.

of the annular path being defined by a ring-shaped tube 66 carried by vanes 68 on the cap 62 and located adjacent to the free radial edges of the impeller vanes 68. This tube 66 causes the fluid to be pumped by the impeller vanes into the cap which redirects the fluid inwardly to the fluid motor.

The cap 62 supports the directing vanes 68 in the fluid path, and the vanes are so arranged as to direct the flow inwardly with a tangential component or circumferential direction of flow, as shown in Fig. 4, against the vanes 78 on the rotor 72, constituting the vane type fluid motor, thereby causing the rotor 72 to turn. The rotor has a shaft 74 from which the accessories may be driven. It will be apparent that the rotor or motor runner 72 rotates continuously in one direction since the fluid set in motion by the impeller vanes 68 is directed at the same angle against the rotor vanes regardless of which direction the impellers 68 is moving. The rotor vanes 78 are preferably so arranged as to take advantage of all of the energy of the pump fluid and in this way will assure an adequate supply of power for the accessory drive.

The inner part of the annular path for the fluid, which, as will be apparent, is continuously circulated by the impeller vanes 68, is defined by curved surfaces 76 and 78 on the impeller 56 and rotor 72, respectively. A supply of fluid for the accessory drive may be provided through the shaft 54 from a pipe 80 communicating with a groove 82 in the bearing 84 which supports the shaft and which may be a part of the housing 58. Fluid from the groove 82 enters the shaft through radial passages 86 and thence through an axial passage 88 to other radial passage 90 communicating with the annular fluid space. The cap 62 may be provided with vents 92 by which the accessory drive may be rendered inoperative by cutting off the supply of fluid through the pipe 80.

It is to be understood that the invention is not limited to the specific embodiment herein illustrated and described, but may be used in other ways without departure from its spirit as defined by the following claims.

I claim:

1. In a fluid drive, an oscillating centrifugal pump, a rotary vane type motor, and a housing having stationary vanes therein for guiding the fluid against the motor vanes, said housing being constructed to define a fluid path from the discharge of the pump through the stationary vanes to the motor inlet.

2. In a fluid drive, an oscillating centrifugal pump, a rotary vane type motor, and a housing having stationary vanes therein for guiding the fluid against the motor vanes, said housing being constructed to define a fluid path from the discharge of the pump through the stationary vanes to the motor inlet, the pump and motor being constructed to form a path for fluid from the motor discharge to the pump inlet.

3. In a fluid drive, an oscillating centrifugal pump including a disc having a row of radial vanes on one side surface thereof, a rotary vane type motor including a disc having its axis substantially coincident with the axis of the pump disc and having a row of vanes on the surface adjacent to the pump disc, and a housing having stationary vanes therein for guiding the fluid from the pump against the motor vanes, said housing extending around said discs to define a fluid path from the outer surfaces of the pump

vanes to the outer surfaces of the motor vanes with the stationary vanes located in said path.

4. In a fluid drive, an oscillating centrifugal pump including a disc having a row of radial vanes on one side surface thereof, a rotary vane type motor including a disc having its axis substantially coincident with the axis of the pump disc and having a row of vanes on the surface adjacent to the pump disc, and a housing having stationary vanes therein for guiding the fluid from the pump against the motor vanes, said housing extending around said discs to define a fluid path from the outer surfaces of the pump vanes to the outer surfaces of the motor vanes with the stationary vanes located in said path, the pump and motor discs being constructed to form a path for fluid from the motor discharge to the pump inlet.

5. In a fluid drive, an oscillating centrifugal pump including a disc having a row of radial vanes on one side surface thereof, a rotary vane type motor including a disc having its axis substantially coincident with the axis of the pump disc and having a row of vanes on the surface adjacent to the pump disc, and a housing having stationary vanes therein for guiding the fluid from the pump against the motor vanes, said housing extending around said discs to define a fluid path from the outer surface of the pump vanes to the outer surfaces of the motor vanes with the stationary vanes located in said path, the pump and motor discs being constructed and arranged to impart a circumferential direction of flow to the fluid delivered by the pump.

35 6. In a fluid drive, an oscillating centrifugal pump including a disc having a row of radial vanes on one side surface thereof, a rotary vane type motor including a disc having its axis substantially coincident with the axis of the pump disc and having a row of vanes on the surface adjacent to the pump disc, and a housing having stationary vanes therein for guiding the fluid from the pump against the motor vanes, said housing extending around said discs to define a fluid path from the outer surface of the pump vanes to the outer surfaces of the motor vanes with the stationary vanes located in said path, the pump and motor discs being constructed to define the inner wall of the fluid passage for directing fluid from the pump vanes over the stationary vanes and onto the motor vanes.

7. In a free-piston unit, opposed pistons, a cylinder in which said pistons reciprocate, and a linkage connecting said pistons, a part of said linkage having oscillatory motion, in combination with a rotary shaft, and means for driving the rotary shaft from said unit including a centrifugal pump connected to the linkage and a rotary fluid motor connected to said shaft and driven by fluid under pressure from said pump.

8. In a free-piston unit, opposed pistons, a cylinder in which said pistons reciprocate, and a linkage connecting said pistons, a part of said linkage having oscillatory motion, in combination with a rotary shaft, and means for driving the rotary shaft from said unit including a centrifugal pump connected to the linkage and a rotary fluid motor connected to said shaft and driven by fluid under pressure from said pump, and a housing surrounding said pump and motor and being constructed to form a path for fluid from the pump discharge to the motor inlet.

9. In a free-piston unit, opposed pistons, a cylinder in which said pistons reciprocate, and

a linkage connecting said pistons, a part of said linkage having oscillatory motion, in combination with a rotary shaft, and means for driving the rotary shaft from said unit including a centrifugal pump connected to the linkage and a rotary fluid motor connected to said shaft and driven by fluid under pressure from said pump, and a housing surrounding said pump and motor and being constructed to form a path for fluid from the pump discharge to the motor inlet, 10 said housing having stationary vanes arranged to impart a tangential velocity to the fluid and located in the fluid path from the pump discharge and the motor inlet.
